H. H. PALS

DOOR

Filed March 8, 1922

Fig. 4.

Inventor
Henry K. Pals,

Arthur M. Hood
Attorney

UNITED STATES PATENT OFFICE.

HENRY H. PALS, OF MESERVEY, IOWA.

DOOR.

Application filed March 8, 1922. Serial No. 541,938.

To all whom it may concern:

Be it known that I, HENRY H. PALS, a citizen of the United States, residing at Meservay, in the county of Cerro Gordo and 5 State of Iowa, have invented a new and useful Door, of which the following is a specification.

The object of my invention is to produce a swinging door construction especially applicable for use in stock pens and the like. 10

One of the objects of my invention is to provide a very cheap construction which, however, will be of such character that stock can not be injured by projecting parts. 15

15 The accompanying drawings illustrate my invention: Fig. 1 is a side elevation; Fig. 2, a section on line 2—2 of Fig. 1; Fig. 3, a section on line 3—3 of Fig. 1 and Fig. 4 a fragmentary section on line 4—4 of 20 Fig. 1.

In the drawings, 10 indicates a door frame which may be either an integral or a structural part of a stall, fence, door, partition, etc. The swinging door 11 is conveniently 25 formed of a plurality of boards 11' held together by rods 12 passing through the boards horizontally. Rods 12 are provided at one end with integral eyes 13 and at the other end are threaded to receive the clamping nuts 14. The eyes 13 are of sufficient 30 size to receive a length of gas pipe 15 which is slightly longer than the door and thus affords projected ends which seat in suitable sockets 16 in frame 10.

35 Sleeved over pipe 15 beneath the eye 13 of the lower rod 12 is a thimble 17 of larger diameter pipe having a length slightly greater than the distance from the lower rod 12 to the bottom of the door so as to 40 engage a wearing washer 18 laid upon the lower sill of the frame 10 around the lower end of pipe 15.

45 At the upper free corner of the door, I provide a vertical notch 25 and a pin 26 which bridges the notch 25 and to which is secured the lower end of a cable 27 passed upwardly through the upper bar of frame 10, preferably between a pair of rollers 28, and from thence over the pulley 29, and provided at its opposite end with a counterweight 30 which may be so arranged as 50 to slide up and down in a channel formed in one of the vertical members 10' of the frame 10. It will be noted that by this 55 arrangement of the counterweight, the door will be held normally in a medial position

from which it may be opened in either direction, the counterweight 30 having the same effect in either case.

In order to lock the door in closed position, I provide a pin 31 projected downwardly through a suitable perforation in the upper bar of frame 10 and into a perforation 32 in the upper edge of door 11. 60 By withdrawing the pin 31, swinging the door slightly to one side, and returning the pin 31 to position, it will be noted that the pin will then serve as a stop to prevent the door swinging in an opening direction in one way but leaves the door free to swing 65 open in the opposite direction. Under such conditions, the door may be set for either ingress or egress and at the same time to prevent egress or ingress. 70

In order to properly fill the opening in 75 the frame 10, and to also cover projecting parts to prevent injury to stock, the forward or free edge of the door is formed with a U-shaped strip of sheet metal 35 which covers the nuts 14 and projecting ends 80 of the rods 12 and lies close to the vertical bar 10' of the door frame. Similarly, a U-shaped strip of sheet metal 36 is secured to the hinged edge of the door and extended around and embraces the eyes 13 and 85 thimble 17.

I claim as my invention:

1. A swinging door having a plurality of hinge eyes secured at one edge, a hinge pin extending through said eyes and secured at its opposite ends in a supporting frame, and a U-shaped strip of sheet metal covering said hinge connection and secured to the sides of the door. 90

2. A door formed of a plurality of boards, bolts passing laterally through said boards and clamping the same together, said bolts carrying eyes at one end, a hinge pin projecting through said eyes and projecting beyond said door to form a support therefor 100 and a cover plate secured over said eyes and hinge pin to form a closure therefor.

3. A door formed of a plurality of boards, bolts passing laterally through said boards and clamping the same together, said bolts carrying eyes at one end and a hinge pin projecting through said eyes and projecting beyond the door to form a support therefor, a cover plate for enclosing said eyes and hinge pin secured to the door, and a second 105 cover plate at the opposite edge of the door covering the ends of said bolts. 110

4. A door formed of a plurality of boards, bolts passing laterally through said boards and clamping the same together, said bolts carrying eyes at one end and a hinge pin projected through said eyes and projecting beyond the door to form a support therefor, a U-shaped cover plate arranged along the edge of the door and secured to the sides thereof to enclose said pin and eyes, and a

second U-shaped cover plate arranged along the opposite edge of the door and secured to the sides thereof to enclose the ends of the bolts.

In witness whereof, I, HENRY H. PALS, have hereunto set my hand at Meservay, Iowa.

HENRY H. PALS.
